UNITED STATES PATENT OFFICE.

EDMOND M. TUDOR BODDAM, OF MELBOURNE, VICTORIA, ASSIGNOR OF
ONE-TENTH TO GEORGE GARIBALDI TURRI, OF SAME PLACE.

PRODUCING AND STORING GAS UNDER HIGH PRESSURE.

SPECIFICATION forming part of Letters Patent No. 605,217, dated June 7, 1898.

Application filed October 29, 1896. Serial No. 610,504. (No model.)

To all whom it may concern:

Be it known that I, EDMOND MEYER TUDOR BODDAM, engineer, a subject of the Queen of the United Kingdom of Great Britain and Ireland, and a resident of 159 Queen street, Melbourne, in the Colony of Victoria, have invented an Improved Method of and Apparatus for Producing and Storing Gas Under High Pressure for Propulsion and other Purposes, 10 of which the following is a specification.

This method of producing and storing gas consists in the gradual combustion in rapid succession of a number of small charges of a slow-burning smokeless gas-producing compound by means of suitable machinery and ignition appliances in a sufficiently strongly constructed and commodious receiver, from which it can be released as required for any suitable purpose, such as the propulsion of 20 shell-torpedoes and other warlike missiles.

While various well-known explosive compounds are adapted for the purpose herein referred to, I prefer nitrated guncotton, having mixed therewith about eight per cent., 25 more or less, of nitroglycerin, and one-half per cent., more or less, of some such substance as urea. This compound is preferably made up in cylindrical charges of great density and is preferably unperforated, so as to burn 30 slowly, preferably entirely from one end.

Reference is had to the accompanying drawings, in which the same parts are indicated by the same numerals throughout the several views.

35 Figure 1 represents an end view of the apparatus as seen from the left of Figs. 2 and 3. Fig. 2 represents a central vertical section made by the plane $x-x$ of Figs. 1 and 3. Fig. 3 represents a plan view, partly in section, the section being that of the horizontal plane $y-y$ of Fig. 2. Fig. 4 represents an end elevation, the rotating disk with chambers therein for the charges of explosive material; and Fig. 5 represents a sectional elevation of 40 a part of a main receiver connected to a secondary or firing receiver and illustrates the means of recharging the secondary receiver automatically.

The combustion chamber and receivers are 50 constructed as follows: A forged or cast steel body 1, rectangular in section and hav-

ing a circular projection 2 on one end eccentric with the central line of the body, is used as a central piece or receiver-body. In approximately the center of this body 1 is a 55 combustion-chamber 3 of suitable diameter and having one closed end 5—viz., that end remote from the cylindrical eccentric projection. Above and below this combustion-chamber and left solid at the end next the cylindrical projection 2 are also formed smaller chambers 6 6, each connected vertically with the central combustion-chamber by small passages 7 7. Corresponding and in the same vertical plane with these are the horizontal passages 8 8 from the three chambers aforesaid, each leading into a solid-ended tube 9 9 of suitable length and diameter, suitably secured to the central piece, and thus together forming a receiver of any suitable or desired capacity. 70 One of the longitudinal chambers 6, preferably the upper one, is closed near its end, as by a screw-plug 6^a, (see Fig. 2,) and the two interrupted parts of the chamber are connected by the passages 10 and 10^a and the 75 valve-chamber 11, the continuity of this passage being controlled by a suitable valve 63. The passage 10^a opens into the short portion of the chamber 6, between the plug 6^a and the 80 perforated screw-plug 6^b, through which latter passes the distributing-pipe 12, preferably flanged on its inner end, as at 12^a, and the joint is protected from leakage by a suitable packing-ring or gas-check 12^b. The end of the other, preferably the lower, chamber 6, 85 is closed by a screw-plug 6^c, preferably made removable, so that the solid matter deposited from combustion may be washed out when desired.

The circular eccentric projection 2 at the 90 end of the central forging has screwed over it a cylindrical collar 13, having an annular rib 14, projecting inward toward its axis. This rim 14 incloses and holds in place a projecting rim 15 on a circular disk 16 of sufficient thickness to have bored therein chambers 17 large enough to contain the cylinders of combustible or explosive composition. These chambers 17 are bored equidistant from the center and arranged to pass serially over the open end of the combustion-chamber 18 when the disk is turned. The 95 100

contiguous faces 19 of the eccentric projection and of the disk containing the chambers are fitted true, and the mouths of the chambers 17 are included within an annular packing-ring 20, which prevents the escape of much gas between the surfaces of the chamber, disk, and the projection 2. Any suitable number of chambers 17 are bored in the disk 16 to contain the charges, and one chamber 21 is constructed to contain a valve 22, preferably a piston-balanced valve, for closing the open end 18 of the combustion-chamber.

To close the rear openings in the chambered disk, another disk 23 of suitable diameter is provided, sliding backward and forward on guide-rods 24, fixed in the chambered disk 16 and on the large central pivot-bolt 25. This pivot-bolt 25 is securely held in the disk 16 against rearward pressure by means of the shoulder 25^a, and is provided just clear of the chamber-closing disk 23 with interrupted screw-threads 27, engaging with corresponding screw-threads on the locking-nut 26, operated by the hand-lever 26^a. The rear end 25 of the bolt 25 is reduced in diameter to allow the nut 26 to slide freely to the rear when it is disengaged from the interrupted screw-threads 27. The bolt 25 is preferably rigidly held in the chambered disk 16, as by shrinking on the disk or by keys 16^a, as shown in Fig. 4.

The disk 23, on its face opposite to each chamber 17, has an obturating-pad 28, forming a substantially gas-tight joint against the edge of each chamber when the disk 23 is clamped home by the interrupted screw 27 and nut 26.

An opening 29 is left in the chamber-closing disk 23 to enable the valve 22 to be opened and closed before the disk 23 is withdrawn for loading or the chambered disk 16 rotated. The valve 22 is shown as screwed down by means of the valve-rod 21^a and hand-wheel 21^b, and the valve-rod is supported by the hanger 21^c, dependent from the washer 21^d, slipped over the free end of the bolt 25; but any suitable form of valve or means for operating the same may be adopted, if desired, as I do not claim the construction of the valve or its details as a part of my invention.

The chambered disk 16 and the chamber-closing disk 23, clamped to it, may be rotated by hand or by suitable gearing, but preferably by means of the gearing hereinafter described. A shaft 47 is rotated by means of any suitable motive power, indicated, for instance, by the pulley 48. This shaft 47 carries a worm 49, which gears with a worm-wheel 50, fixed to the circumference of the chambered disk 16. The shaft 47 is free to move in the direction of its length in its bearings, and the end 51 presses against the volatile spring 52. On the shaft 47 is a friction-pulley 53, pressing against another friction-pulley 54, which in its turn presses against the friction-pulley 55, (see Fig. 3,) working on the shaft 56, and thus moving the worm

57 in the same direction as the worm 49. The worm 57 gears into the worm-wheel 58, having two sets of teeth 59 60 on its rim, the set 60 gearing with a small pinion 61, which has fast to its shaft 62 a cam-lever 39, arranged to push backward the catch-pin 40, fixed to the bolt 41, and release the disk 16. This bolt being normally pressed against the face of the disk 16, as will be hereinafter described, enters the recesses 64 left in the chambered disk 16 just as each chamber comes opposite to the end of the combustion-chamber 18, and thus locks the chambered disk in the proper position for firing a charge until released by the cam-lever 39. Rotation being given to the shaft 47, the shaft 56 also rotates, and consequently both the chambered disk 16 and cam-pinion 61 are rotated until the cam-lever 39 releases the catch-pin 40 and the bolt moves forward and holds the disk 16. The cam-lever, however, continues to travel around and releases the bolt at each revolution, thus allowing the chambered disk to rotate through the angle subtended by the arc between the centers of two of the chambers for each revolution of the cam-lever 39.

During the stoppage of the chambered disk 16 the worm 49 and shaft 47 do not stop revolving, but are pushed bodily to the left, compressing the spring 52 instead of turning the disk 16, and thus a step-by-step motion is imparted to the chambered disk and a continuous movement to the cam-lever 39. The chambers 17 are thereby successively brought opposite to the opening in the combustion-chamber 18, and the charges contained therein are ignited, as hereinafter described.

The rod 41 is periodically pushed to the right by the lever 39, as hereinbefore described, and the rod 42 is normally pressed in the reverse direction by means of the coil-spring 42^a, (see Fig. 2,) and thus reciprocating motion is imparted to the catch-pin 40. A further result of the reciprocating motion of the rods 41 and 42 is to supply the primers *seriatim* for firing the several charges in the chambers 17. This is done as follows: A vent or firing-channel 30 is bored through the receiver-body 1 from just above the firing-chamber 18 to a point in the upper surface of the receiver-body just below the slide 31, which slide is reciprocated in the chamber 32 by means of the rods 41 and 42, as before described. This vent 30 registers with a corresponding vent 30^a, connecting the front face of the disk 16 with its corresponding chamber 17 when the said chamber is in the firing position. Thus it will be seen that when each chamber is in the firing position there will be a continuous passage from the base of the slide 31 to that one of the chambers that is to be fired. This slide 31 is perforated, as shown in Fig. 1, the upper portion of the perforation being somewhat enlarged to form a primer-chamber 33, capable of receiving a suitable primer, electric or otherwise, but preferably an electric primer. The lower orifice of this primer-chamber is so ar-

ranged as to register with the upper orifice of the vent 30 when the slide 31 reaches that limit of its travel that coincides with the locked position of the chambered disk 16, at 5 which time it will be seen that there is a continuous vent or passage from the primer to the charge about to be fired.

Over the slide 31 and in the line of travel of the primer-chamber 33 a circular opening 10 is left in the cover of the chamber, in which a tube 37, containing (one above the other) the requisite number of primers 38 for a complete revolution of the chamber-disks, are placed, so that the primers 38 will drop into 15 the slide in succession by gravity. The slide as it is pushed forward by the cam-lever 39 in the chamber 32 receives at the end of its stroke from the tube 37 a single primer, which drops down into the primer-chamber 31. As 20 soon as the rotation of the cam 39 releases the catch-pin 40, the slide 31 will be pushed to the farthest limit of its travel in the opposite direction by means of the spring 42^a, and when the catch-pin 40 locks the disk 16 the 25 primer will be over the vent 30 and ready for firing.

The firing may be accomplished by means of an electric battery attached to the wires 35 or in any other convenient way. 30 It will be obvious that any mechanic skilled in electricity could so arrange the electrical connections that each primer could be fired automatically as soon as the several parts arrive at the firing position, and thus the several charges might be fired automatically; but this being a mere matter of arrangement and not, properly speaking, a part of my invention will not be further described.

In order to prevent excessive pressure from 40 being generated in the receiver, the herein-after-described safety attachment is provided. A piston 44, located near the end of the chamber 3, bears against heavy cup-springs 45, which are compressed between the 45 said piston and the screw-plug 5. The piston 44 is provided with suitable gas-check 44^g. This plug may be perforated, as at 5^a, to relieve the back pressure from leakage around the piston 44, as is well known in 50 kindred devices. To the piston is attached the piston-rod 44^a, carrying the stout resilient arm 44^b, Fig. 2, connected by the rod 46 to the lever 46^c, Fig. 3, which operates the locking-bolt 43, constructed like the catch-pin 41, 55 to engage in one of the holes 64 in the disk 16.

When the pressure becomes excessive in the receiver, the piston 44 moves backward against the opposing pressure of the cup-springs, causing the resilient arm to bend 60 somewhat, pressing the bolt 43 against the face of the disk 16, until one of the holes 64 is in position to be engaged by the locking-bolt 43, when the said bolt will slide into the said hole and will lock the disk 16 against 65 further rotation, until the pressure in the receiver falls low enough to permit the cap-

springs 45 to return the piston 44 to the initial position. Thus it will be seen that when the pressure in the receiver exceeds a predetermined limit, regulated by means of the 70 springs 45, no further charges can be fired into the receiver. As an additional provision against accidents any suitable safety-valve may be employed; but these being well known for kindred purposes are not shown 75 or described.

The receiver may be discharged through the slide-valve 63 in the chamber 11, which may be operated in any convenient way, or any other well-known form of discharge-valve 80 may be adopted, if desired.

In order to provide for automatic closing of the discharge-valve when the secondary receiver, such as is shown in my application, Serial No. 610,505, filed October 29, 1896, and 85 entitled "Improvements in pneumatic guns," is charged to the requisite pressure, I provide the arrangement shown in Figs. 2 and 5, where the slide-valve 63 has its stem 65 terminate at one end in the piston 66 and at the 90 other end is provided with a collar 69, bearing against the volute spring 70. The pipe 68 is connected to the escape-pipe 68^a from the safety-valve 71 of the secondary receiver, preferably through an interposed reservoir 95 chamber or dome 72, although this is not necessary. This safety-valve 71 has a small hole 71^a therethrough to allow a small amount of gas to flow through in either direction. As soon as the safety-valve of the secondary 100 receiver begins to blow off, the pressure therefrom will enter the cylinder 67 through the pipe 68, and will press the piston backward against the action of the spring 70, causing the valve 63 to assume the closed position 105 shown in Figs. 2 and 5. Now if the secondary receiver be discharged or its pressure lowered, as in firing a gun therefrom, part of the gas from cylinder 67 will flow through the hole 71^a into the secondary receiver, reducing the pressure in the cylinder 67. When the pressure in the cylinder 67 falls, the spring 70 again opens the valve 63, and thus automatic charging of the secondary receiver is again effected. In 110 this manner the secondary receiver is charged and recharged from the main receiver automatically and without excessive shock. The secondary receiver (shown in detail in my application, Serial No. 610,505, before referred to) is indicated in Fig. 5 by the central portion 115 1^a and the tubes 9^a, connected by the pipe 12 with the main receiver and opening, as at 12^a, into the pipes or other passages connected to the gun to be fired. The 120 will be obvious that a plurality of such secondary receivers may be connected to the main or central receiver to be charged and recharged automatically, as has just been described.

It will be obvious that various modifications of the herein-described apparatus might be 130 made which could be used without departing from the spirit of my invention.

Having thus described my invention, what I claim, and desire to secure by Letters Patent of the United States, is—

1. The method of production and storage of gases under pressure which consists in successively firing a number of small charges of a smokeless explosive into a receiver or storage-chamber of sufficient strength, and automatically stopping the further firing of said charges when the pressure in said receiver exceeds a predetermined limit, substantially as described.
2. The method of production, storage, and distribution of gases under pressure which consists in successively firing a number of small charges of explosive into a main receiver, and in automatically charging from said main receiver one or more secondary receivers whenever the pressure in said secondary receivers falls below a predetermined limit, substantially as described.
3. The method of production, storage, and distribution of gases under pressure which consists in successively firing a number of small charges of explosive into a main receiver, and in automatically charging from said main receiver one or more secondary receivers whenever the pressure in said secondary receivers falls below a predetermined limit, and also automatically stopping the further firing of said charges when the pressure in the main receiver exceeds a predetermined limit, substantially as described.
4. An apparatus for the production and storage of gases under pressure, comprising a plurality of strong hollow cylinders secured to a heavy chambered central piece, the chambers in said cylinders and in said central piece communicating with one another, means for successively firing a plurality of small charges into the said system of chambers, and means for automatically stopping the further firing of said charges when the pressure of the gases exceeds a predetermined limit, substantially as described.
5. An apparatus for the production and storage of gases under pressure, comprising a plurality of strong hollow cylinders secured to a heavy chambered central piece, the chambers in said cylinders and in said central piece communicating with one another, a firing-chamber in said central piece, a chambered disk for holding a plurality of small explosive charges, means for rotating said disk and causing said charges to register *seriatim* with said firing-chamber and means for firing said charges, substantially as described.
6. An apparatus for the production and storage of gases under pressure, comprising a plurality of strong hollow cylinders secured to a heavy chambered central piece, the chambers in said cylinders and in said central piece communicating with one another, a firing-chamber in said central piece, a chambered disk for holding a plurality of small explosive charges, means for rotating said disk and causing said charges to register *seriatim* with said firing-chamber and means for firing said charges, substantially as described.

said firing-chamber, and means for firing said charges, means for successively firing a plurality of small charges into the said system of chambers, and means for automatically stopping the further firing of said charges when the pressure of the gases exceeds a predetermined limit, substantially as described.

7. An apparatus for the production and storage of gases under pressure, comprising a plurality of strong hollow cylinders secured to a heavy chambered central piece, the chambers in said cylinders and in said central piece communicating with one another, means for successively firing a plurality of small charges into the said system of chambers, and means for automatically stopping the further firing of said charges when the pressure of the gases exceeds a predetermined limit, comprising a piston, heavy springs bearing against the rear face of said piston and resisting the pressure in the central chamber, and stop mechanism operated by said piston and controlling the further movement of said chambered disk, substantially as described.

8. An apparatus for the production and storage of gases under pressure, comprising a plurality of strong hollow cylinders secured to a heavy chambered central piece, the chambers in said cylinders and in said central piece communicating with one another, a firing-chamber in said central piece, a chambered disk for holding a plurality of small explosive charges, means for rotating said disk and causing said charges to register *seriatim* with said firing-chamber, means for firing said charges, and means regulated by the rise of pressure of the gases for stopping the rotation of the chambered disk and the further firing of said charges, and thus automatically regulating the pressure to a predetermined limit, substantially as described.

9. An apparatus for the production and storage of gases under pressure, comprising a plurality of strong hollow cylinders secured to a heavy chambered central piece, the chambers in said cylinders and in said central piece communicating with one another, a firing-chamber in said central piece, a chambered disk for holding a plurality of small explosive charges, means for rotating said disk and causing said charges to register *seriatim* with said firing-chamber, and means for firing said charges, and means for automatically stopping the further firing of said charges when the pressure of the gases exceeds a predetermined limit, comprising a piston, heavy springs bearing against the rear face of said piston and resisting the pressure in the central chamber, and stop mechanism operated by said piston and controlling the further movement of said chambered disk, substantially as described.

10. An apparatus for the production, storage, and distribution of gases under pressure, comprising a main receiver and one or more secondary receivers connected thereto, means for successively firing a plurality of small

charges of explosive material into said main receiver, and means for automatically charging and recharging said secondary receiver or receivers from the main receiver when the 5 pressure in the secondary receiver or receivers falls below a predetermined limit, substantially as described.

11. An apparatus for the production, storage and distribution of gases under pressure, 10 comprising a main receiver and one or more secondary receivers connected thereto, means for successively firing a plurality of small charges of explosive material into said main receiver, means for automatically checking 15 the firing of said charges when the pressure in the main receiver exceeds a predetermined limit, and means for automatically charging and recharging said secondary receiver or receivers from the main receiver when the pressure 20 in the secondary receiver or receivers falls below a predetermined limit, substantially as described.

12. An apparatus for the production, storage, and distribution of gases under pressure, 25 comprising a main receiver and one or more secondary receivers connected thereto, each of said receivers comprising a heavy chambered central piece and a plurality of strong hollow cylinders secured thereto, the chambers 30 in said cylinders and in said central piece communicating with one another, means for successively firing a plurality of small charges of explosive material into said main receiver, and means for automatically charging 35 and recharging said secondary receiver or receivers from the main receiver when the pressure in the secondary receiver or receivers falls below a predetermined limit, substantially as described.

40 13. An apparatus for the production, storage and distribution of gases under pressure, comprising a main receiver and one or more secondary receivers connected thereto, each of said receivers comprising a heavy chambered central piece and a plurality of strong hollow cylinders secured thereto, the chambers 45 in said cylinders and in said central piece communicating with one another, means for successively firing a plurality of small charges of explosive material into said main receiver, means for automatically checking the firing 50 of said charges when the pressure in the main receiver exceeds a predetermined limit, and means for automatically charging and recharging 55 said secondary receiver or receivers from the main receiver when the pressure in the secondary receiver or receivers falls below a predetermined limit, substantially as described.

60 14. An apparatus for the production, storage, and distribution of gases under pressure, comprising a main receiver and one or more secondary receivers connected thereto, means for successively firing a plurality of small 65 charges of explosive material into said main receiver, and means for automatically charging and recharging said secondary receiver or

receivers from the main receiver when the pressure in the secondary receiver or receivers falls below a predetermined limit, comprising a safety-valve on the secondary receiver, a spring-operated valve on the main receiver normally closing the connecting-passage from the main receiver to the secondary receiver, and means operated by the escape 75 of fluid past said safety-valve for closing the former valve against the action of said spring, substantially as described.

15. An apparatus for the production, storage and distribution of gases under pressure, 80 comprising a main receiver and one or more secondary receivers connected thereto, means for successively firing a plurality of small charges of explosive material into said main receiver, means for automatically checking 85 the firing of said charges when the pressure in the main receiver exceeds a predetermined limit, and means for automatically charging and recharging said secondary receiver or receivers from the main receiver when the pressure 90 in the secondary receiver or receivers falls below a predetermined limit, comprising a safety-valve on the secondary receiver, a spring-operated valve on the main receiver normally closing the connecting-passage 95 from the main receiver to the secondary receiver, and means operated by the escape of fluid past said safety-valve for closing the former valve against the action of said spring, substantially as described.

16. An apparatus for the production, storage, and distribution of gases under pressure, comprising a main receiver and one or more secondary receivers connected thereto, means for successively firing a plurality of small 105 charges of explosive material into said main receiver, and means for automatically charging and recharging said secondary receiver or receivers from the main receiver when the pressure in the secondary receiver or receivers falls below a predetermined limit, comprising a perforated safety-valve on the secondary receiver, a spring-operated slide-valve on the main receiver and normally closing the connecting-passage from the main receiver to the 110 secondary receiver, a piston-rod fast to said valve, a piston on said rod, and a cylinder 115 enclosing said piston and connected to the escape-pipe from said safety-valve, substantially as described.

17. An apparatus for the production, storage and distribution of gases under pressure, comprising a main receiver and one or more secondary receivers connected thereto, means for successively firing a plurality of small 125 charges of explosive material into said main receiver, means for automatically checking the firing of said charges when the pressure in the main receiver exceeds a predetermined limit, and means for automatically charging 130 and recharging said secondary receiver or receivers from the main receiver, when the pressure in the secondary receiver or receivers falls below a predetermined limit, comprising

- a perforated safety-valve on the secondary receiver, a spring-operated slide-valve on the main receiver and normally closing the connecting-passage from the main receiver to the 5 secondary receiver, a piston-rod fast to said valve, a piston on said rod and a cylinder in-closing said piston and connected to the escape-pipe from said safety-valve, substantially as described.
- 10 18. In an apparatus of the character described the means for controlling the pressure in the main receiver which consists of a piston, subjected on one side to the pressure of the gases, strong cup-springs bearing on the 15 other side of said piston, a piston-rod projecting from said piston and apparatus regulated by the motion of said piston against said springs for checking the further discharge of pressure-producing charges, substantially as 20 described.
19. In an apparatus of the character described the means for controlling the pressure in the main receiver which consists of a piston subjected on one side to the pressure of the gases, strong cup-springs bearing on the 25 other side of said piston, a piston-rod projecting from said piston and stop mechanism operated by the motion of said piston-rod for stopping the operation of the pressure-producing 30 apparatus, substantially as described.
20. In an apparatus of the character described, the combination with a firing-chamber, of a centrally-pivoted disk provided with a plurality of cartridge-chambers grouped in 35 a circle about said pivot, means for imparting a step-by-step motion to said disk, means for separately supplying primers to the apparatus, and means for firing said primers, substantially as described.
- 40 21. In an apparatus of the character described, the combination with a firing-chamber, of a centrally-pivoted disk provided with a plurality of cartridge-chambers grouped in a circle about said pivot, means for imparting a step-by-step motion to said disk, means for separately supplying primers to the apparatus, and means for firing said primers, substantially as described.
- 45 22. In an apparatus of the character described, the combination with a firing-chamber, of a centrally-pivoted disk provided with a plurality of cartridge-chambers grouped in a circle about said pivot, means for simultaneously imparting a step-by-step motion 50 to said disk, and for separately supplying primers to the apparatus, and means for firing said primers, substantially as described.
- 55 23. In an apparatus of the character described, the combination with a firing-chamber, of a centrally-pivoted disk provided with a plurality of cartridge-chambers grouped in a circle about said pivot, means for imparting a step-by-step motion to said disk, means for separately supplying primers to the apparatus, and means for firing said primers with 60 means operated by the pressure of the gases for stopping the motion of said disk when the pressure exceeds a predetermined limit, substantially as described.
24. In an apparatus of the character described, the combination with a firing-chamber, of a centrally-pivoted disk provided with a plurality of cartridge-chambers grouped in a circle about said pivot, means for imparting a step-by-step motion to said disk, means for separately supplying primers to the apparatus, and means for automatically firing said primers, with means operated by the pressure of the gases for stopping the motion of said disk when the pressure exceeds a predetermined limit, substantially as described.
- 70 25. In an apparatus of the character described, the combination with a firing-chamber, of a centrally-pivoted disk provided with a plurality of cartridge-chambers grouped in a circle about said pivot, means for simultaneously imparting a step-by-step motion to said disk, and for separately supplying primers to the apparatus, and means for firing said primers, with means operated by the 80 pressure of the gases for stopping the motion of said disk when the pressure exceeds a predetermined limit, substantially as described.
- 75 26. In an apparatus of the character described, the combination with a firing-chamber, of a centrally-pivoted disk provided with a plurality of cartridge-chambers grouped in a circle about said pivot, means for simultaneously imparting a step-by-step motion to said disk, and for separately supplying primers to the apparatus, and means for automatically firing said primers, with means operated by the pressure of the gases for stopping the motion of said disk when the pressure exceeds a predetermined limit, substantially as described.
- 85 27. In an apparatus of the character described, the combination with a firing-chamber, of a centrally-pivoted disk provided with a plurality of cartridge-chambers grouped in a circle about said pivot, means for simultaneously imparting a step-by-step motion to said disk, and for separately supplying primers to the apparatus, and means for automatically firing said primers, with means operated by the pressure of the gases for stopping the motion of said disk when the pressure exceeds a predetermined limit, substantially as described.
- 90 28. In an apparatus of the character described, the combination with a firing-chamber, of a centrally-pivoted disk provided with a plurality of cartridge-chambers grouped in a circle about said pivot, means for simultaneously imparting a step-by-step motion to said disk, and for separately supplying primers to the apparatus, and means for automatically firing said primers, with means operated by the pressure of the gases for stopping the motion of said disk when the pressure exceeds a predetermined limit, substantially as described.
- 95 29. In an apparatus of the character described, the combination with a firing-chamber, of a centrally-pivoted disk provided with a plurality of cartridge-chambers grouped in a circle about said pivot, means for simultaneously imparting a step-by-step motion to said disk, and for separately supplying primers to the apparatus, and means for automatically firing said primers, with means operated by the pressure of the gases for stopping the motion of said disk when the pressure exceeds a predetermined limit, substantially as described.

In witness whereof I have hereunto set my hand in the presence of two subscribing witnesses.
